UNITED STATES PATENT OFFICE.

HARVEY L. FISHER, OF CHICAGO, ILLINOIS, ASSIGNOR TO H. L. FISHER MFG. CO., INC.,
OF CHICAGO, ILLINOIS, A CORPORATION OF ILLINOIS.

STEREOTYPER'S CASTING MACHINE.

Application filed August 11, 1921. Serial No. 491,486.

To all whom it may concern:

Be it known that I, HARVEY L. FISHER, a citizen of the United States, residing at Chicago, in the county of Cook and State 5 of Illinois, have invented certain new and useful Improvements in Stereotypers' Casting Machines, of which the following is a specification.

My invention relates to a stereotyper's 10 casting machine and more particularly to a machine having a pair of spaced platens against one of which the matrix is placed, being held thereagainst by suitable bars which also serve to confine the molten metal 15 to the desired space between said platens.

In certain machines of this type as heretofore constructed one of the platens has been made stationary and the other movable relatively thereto consequently the metal 20 confining bars which are carried by the movable platen chafe against the other platen when the movable platen is moved into and out of operative engagement with the other platen and after a casting has been 25 made and as the movable platen is moved out of engagement with the other platen, the casting also chafes against the other or stationary platen. Obviously any chafing of metal against metal in a machine of this 30 kind is very undesirable. In certain other machines the movable platen is moved into its approximate working position and is then moved bodily manually against the stationary platen and secured thereagainst by 35 clamping devices at the top and bottom which requires considerable time and labor.

One of the objects of my invention, therefore, is to provide a machine so constructed that both platens are movably mounted and 40 are so arranged that the platens may be brought quickly and conveniently into or out of operative engagement without any chafing of one platen against the other, and without any chafing of the casting formed 45 therebetween against either of said platens, and which will require very few, if any, clamping devices to hold the two platens tightly together.

The invention in its preferred form 50 contemplates a machine having a frame consisting of substantially vertical and horizontal portions; and a further object of my

invention is to provide links for connecting the front and rear platens to the horizontal and vertical frame portions, respectively, 55 and so arranged that the links co-operate to form a toggle locking joint, the preferred arrangement being to connect the rear platen to the vertical frame portion by relatively short links and to connect the front 60 platen to the horizontal frame portion by relatively long links, which arrangement permits the front platen to have a range of movement sufficient to permit it to be swung from a substantially horizontal, or what 65 may be termed a "make-up," position over adjacent and into operative engagement with the substantially vertically positioned rear platen, the front platen when in its make-up position serving as a work table 70 on which the matrix and the bars for confining the molten metal may be conveniently arranged.

A further object of my invention is to provide a machine in which one of the 75 platens is adjustable relative to the other whereby the space between the two platens may be varied to form castings of different thicknesses, for example, a casting type high, or, a casting type high having a cored 80 back, or, a casting relatively thin in thickness commonly called a "skiver" and which is secured to a back of wood of sufficient thickness to make the casting and back type high.

A further object of my invention is to provide means which will positively insure the two platens being brought into or out of operative engagement simultaneously and which is preferably of such construction 90 that no adjustments need be made even though one of the platens be adjusted relative to the other to vary the width of the space between said platens for the purpose aforesaid and in this connection my invention contemplates the provision of means, preferably one or more springs, adapted to hold the rear platen up a distance above its operative position, in combination with a pair of lugs secured at both sides to said 95 platens, the lugs secured to the front platen overlapping those secured to the rear platen, whereby when the front platen is swung from its horizontal position to a position 100

adjacent the rear platen, the lugs carried thereby will engage or bear down upon the lugs carried by the rear platen, consequently the front platen forces the rear platen downwardly simultaneously with it against the tension of said springs and without the occurrence of any chafing action.

A further object of the invention is to provide novel means for clamping the upper 10 portions of the two platens together when they are in their operative position.

A further object of the invention is to provide a melting pot for the metal in combination with suitable means for heating 15 the same, which pot is so positioned and so mounted on the frame of the machine that when it is tilted, the metal will flow therefrom into the space between the two platens.

In order to make a casting suitable for the 20 purpose intended the platens, particularly the platen not carrying the matrix, must be preliminarily heated to a proper temperature. In machines of this type as heretofore constructed the platens have been preliminarily heated by making two or three castings which are discarded. This manner of 25 preliminarily heating the platens involves useless labor and expense and requires considerable time. It is a further object of my invention to provide means for preliminarily heating the platen not carrying the matrix which is of such construction that the platen may be heated in a relatively 30 short period of time and while the metal in the melting pot is being brought to the desired temperature.

A further object of the invention is to provide means adapted to preliminarily 40 heat the platen not carrying the matrix and which is of such construction that the wet papier-mâché flongs on the type may be inserted between the platens and dried or baked to form the matrices, thus making it unnecessary to provide separate or special 45 means for baking the flongs.

In machines of this type as heretofore 50 constructed the bars for confining the molten metal to the desired space between the platens have usually been loosely positioned on the movable platen, consequently 55 when the movable platen is swung into operative engagement with the stationary platen, the bars oftentimes slip to one side or the other out of parallelism with the consequent result that the casting is not true, the sides thereof having to be trimmed or shaved off in order to make them true, before it can be used; and it is a further object of my invention to provide novel means 60 for attaching the bottom and side bars to one of the platens, preferably the front platen, which is of such construction that the side bars are positively maintained in parallel relationship and at the right angles 65 to the bottom bar, and which also permits

one of the side bars to be readily moved laterally relative to the other bar to accommodate matrices of different widths.

The invention consists in the novel constructions, arrangements and devices to be hereinafter described and claimed for carrying out the above stated objects and such other objects as will appear from the following description of certain preferred embodiments illustrated in the accompanying drawings, wherein—

Fig. 1 is a perspective view of a machine embodying the principles of my invention;

Fig. 2 is a side elevational view of the machine, on a reduced scale, the front platen 80 being in its make-up position;

Fig. 3 is a side elevational view of the machine, also on a reduced scale, the platens being in their casting position;

Fig. 4 is a rear elevational view of the machine, certain portions thereof being broken away to show certain features which otherwise would be hidden from view;

Fig. 5 is a vertical sectional view of the machine taken on the line 5—5 of Fig. 4;

Fig. 6 is a transverse sectional view taken on the line 6—6 of Fig. 4;

Fig. 7 is a sectional view, on an enlarged scale, taken on the line 7—7 of Fig. 4;

Fig. 8 is a top plan view of the front platen illustrating the means employed for confining the molten metal to the desired space between the platens;

Fig. 9 is an inverted plan view, on an enlarged scale, of one pair of the co-engaging lugs secured to the platens for insuring simultaneous movement of the platens into and out of operative engagement;

Fig. 10 is an elevational view, on an enlarged scale, of a fragmentary portion of one side of the front platen showing one of the side bars for confining the molten metal to the desired space between the platens, the middle portion thereof being broken out;

Fig. 11 is a transverse sectional view taken through the two platens when in operative engagement, a mold member being attached to the rear platen and the metal confining means being slightly modified so that a casting having a cored back may be made; and

Fig. 12 is a vertical sectional view taken on the line 12—12 of Fig. 11.

Like characters of reference designate 120 like parts in the several views.

Referring now to the drawings, the framework of the machine comprises a horizontal portion 15 mounted on suitable supporting legs 16 and which is rigidly secured to, or integrally formed with, an upstanding substantially vertical portion 17. A front platen 18 and a rear platen 19 are swingingly connected to the horizontal and vertical frame portions 15 and 17, respectively. 130

The front platen is pivotally connected at its bottom or rear end to a pair of links 20, the opposite ends of said links being pivotally connected to a pair of upstanding ears 21 formed integrally with and adjacent the front end of the horizontal frame portion 15. The front platen is also pivotally connected to a pair of links 22, the lower ends of which are pivotally connected 5 to the frame portion 15, the links 20 and 22 being relatively long and of such length that the front platen may be swung from a substantially horizontal position, as shown in Fig. 1, to a substantially vertical position, as shown in Fig. 3. A handle 18^a is secured to the front platen to facilitate swinging the front platen from one position to the other.

The rear platen 19 is pivotally connected 20 to a plurality of relatively short links 23 which are pivotally mounted on transversely extending bars 24 slidably mounted in horizontally extending slots 25 formed in the frame portion 17, see particularly Fig. 7. 25 The bars 24 have threaded engagement with horizontally positioned threaded studs 26 each of which projects through a bushing member 27 threaded into the frame portion 17, the studs 26 having a collar 28 which 30 bears against the inner end of the bushing members 27 to limit outward longitudinal movement of the stud. A handle member 29 is secured to each of the studs to facilitate rotation thereof. This arrangement 35 permits the rear platen to be quickly and conveniently moved toward or away from the front platen so that castings of different thicknesses may be made. The threaded portions of the studs 26 snugly engage the 40 bars 24 so that when the desired adjustments have been made, no further attention need be given to this feature of the invention until it is desired to make a casting of a different thickness.

45 A pair of tension springs 30, see Figs. 4 and 5, the upper ends of which are secured to the vertical frame portion 17 and the lower ends of which are secured to the back of the rear platen 19, normally hold said 50 platen upwardly in what may be termed a "preliminary" position substantially as shown in Figs. 1 and 2. A pair of plates 31, see particularly Fig. 9, are secured to the bottom of the rear platen 19 adjacent its 55 sides, each of said plates having a lug 31^a which projects laterally somewhat beyond the sides of the platen. A pair of plates 32, similar to the plates 31, are secured to the bottom of the front platen 18 adjacent its 60 sides each of which has a lug 32^a also extending laterally somewhat beyond the sides of said platen. The lugs 32^a are adapted to engage, or bear down upon, the respective lugs 31^a of the plates 31 when the front 65 platen is brought into what may be termed

its "preliminary" position as shown in dotted lines in Fig. 2. The co-engaging lugs 31^a and 32^a being arranged at the side of the platens, do not interfere in any way with the adjustment of the rear platen to make 70 castings of different thicknesses.

The links 20 and 22 connecting the front platen to the horizontal frame portion in co-operation with the links 23 connecting the rear platen to the vertical frame portion 75 form a toggle arrangement for moving the platens into and out of operative engagement. When the front platen is swung from its make-up position shown in full lines in Figs. 1 and 2 into its preliminary 80 position shown in dotted lines in Fig. 2 the lugs 32^a carried thereby bear down upon the lugs 31^a carried by the rear platen. Movement of the front platen from its preliminary position to its casting position results 85 in the rear platen being forced downwardly simultaneously with the front platen into its casting position and against the tension of the springs 30. As the front platen is moved upwardly from the position shown in 90 Fig. 3 the springs 30 pull the rear platen upwardly simultaneously with the front platen until the rear platen reaches the limit of its upward travel which is the position shown in Figs. 1 and 2 and when that 95 limit has been reached the front platen is in the position shown in dotted lines in Fig. 2, the distance between the adjacent lowermost edges of the two platens being considerably greater than the thickness of the casting being made, consequently, there can be no chafing of the casting against the rear platen or of the metal confining bars, to be described presently, against the rear platen.

The links 20 and the lower pair of links 23 are in substantial alignment when the platens are in operative engagement and by proper adjustment of the bar carrying said links 23 the platens may be forced very 100 tightly together at their lower ends without 105 any additional clamping means. The links 22 and the upper pair of links 23 serve to force the upper ends of the platens together, but since these links are considerably out of alignment and because of the close engagement of the platens at their lower ends, there is a tendency for the platens to spring apart slightly at their upper ends. I preferably provide means, therefore, to insure 110 a tight fit of the platens at their upper ends, which means preferably consists in a pair of clamping members 33 one end of 115 each of said members being pivotally connected to a member 34 swivelly mounted on the sides of the rear platen, the swinging 120 ends of the members 33 being threaded and adapted to slip into engagement with the respective notched members 35 secured to the front platen. A handle portion 36 is 125 threaded on each of the members 33. When 130

the platens are in their open position, the handle members 33 are free to swing downwardly substantially as shown in Figs. 1 and 2 where they are out of the way. When 5 the platens are moved into operative engagement the handle members are swung into a horizontal position, as shown in Fig. 3, being placed in engagement with the members 35 and the handle members 36 are then rotated sufficiently to draw the upper portions 10 of the two platens tightly together.

In order to limit outward swinging movement of the front platen I provide a rod 37 pivotally connected at its upper end to the 15 platen, the lower end of which slidably projects through a member 38 pivoted on a forwardly extending arm 39 formed integrally with the frame portion 15, a collar 40 being fixed to the lower end of the rod 20 37 to limit upward movement thereof through the member 38. If desired, a spring 41 may be provided on the rod 37 between the platen and the member 38 which, it will be noted, will be considerably compressed 25 when the front platen is in its vertical position and will assist in moving said platen from said position into its horizontal position.

A melting pot 42 for the stereo-metal is 30 pivotally mounted between a pair of brackets 43 secured to the upper end of the frame portion 17. The melting pot is provided with a pouring spout 42^a so that when the pot is tilted into the position shown in 35 Fig. 3, the molten metal will flow therefrom into the space between the two platens, the pot being provided with a handle member 44 to facilitate tilting it. A burner 45, see Figs. 4 and 5, of any desired construction, 40 is positioned underneath the melting pot receiving its fuel from a pipe 46 controlled by a valve 47, the pipe 46 being connected with a header 48 which receives fuel from any convenient source. The back of the upper end of the frame portion 17 serves to direct the flames from the burner 45 upwardly against the forward side of the melting pot and a housing member 49 secured to said frame portion serves to direct 45 the flames upwardly against the rearward side of the melting pot. By this arrangement a pot of cold metal may be brought to the desired fluid state in a very short period of time.

I preferably provide means for preliminarily heating both the front and rear sides of the rear platen, and for this purpose a burner 50 is positioned preferably directly under the space between the front and rear platens which is supplied with fuel by a pipe 51 controlled by a valve 52 and connected with the pipe 48. A burner 53 is positioned under the rear platen receiving its fuel from a pipe 54 controlled by a valve 55 and connected with the pipe 48. The

platens are preferably formed with a plurality of horizontally and transversely extending stiffening ribs to prevent warping, the horizontal ribs 19^a of the rear platen being each provided with a plurality of apertures 19^b so that the heated currents of air from the burners 50 and 53, particularly from the burner 53, will pass upwardly therethrough. A sheet metal plate 56 is secured to the sides of the rear platen and to the rear ends of the ribs 19^a, an asbestos lining 57 being preferably interposed between said ribs and said plate. This arrangement provides a flue in the rear platen through which the currents of heated air pass whereby the rear platen may be heated to the proper temperature while the stereo-metal is being heated. With an arrangement as above described it is not necessary to provide any separate or additional means for baking the wet papier-mâché flongs as is customarily done with machines of this type as heretofore constructed.

The means for confining the molten metal to the desired space between the platens is best shown in Figs. 8, 10 and 11 and includes a transversely extending bottom bar 58, which is adapted to be positioned against the lugs 32^a projecting from the plates 32 secured to the front platen, and side bars 59 and 60. The side bar 59 at its rear end is provided with a depending tongue 61 which engages a bracket member 62 secured to the side of the platen, see Fig. 10, and at its forward end is provided with a depending tongue 63 which is adapted to engage a bracket member 64 also secured to the side of said platen. The rear or bottom end of the bar 59 fits snugly into a recess 65 formed in the adjacent side of the bar 58, see Fig. 8, and that end of the bar 59 is provided with a kerf 66 adapted to receive a laterally projecting tongue 67 formed on an angle member 68 which is secured by screws 69 to the bar 58. The tongue 63 is bevelled off at 63^a and comes into snug engagement with the bracket 64, when the bar 59 is flat against the platen, in which position the rear or bottom end of the bar 59 is forced into the bottom of the recess 65 and the bar 58 is pushed firmly against the lugs 32^a. The bar 58 is preferably recessed to receive tongues 32^b formed on the lugs 32^a to prevent longitudinal movement of the bar. It will thus be apparent that when the bars 58 and 59 are in the position shown in Figs. 8 and 10 they are rigidly secured together and to the platen, and that the bar 59 may be raised or positioned obliquely relative to the platen, which, of course, results in tilting or rocking the bar 58 on its rear bottom longitudinally extending edge, without disengaging it from the bar 58. If desired, a screw 70 may be used for securing the bar 59 to the angle iron 68.

The bar 60 is maintained in parallel relationship with the bar 59 preferably by a toggle mechanism comprising a pair of links 71, each being pivotally connected at one end to angle members 72, which are pivotally connected to bracket members 73 secured to the side of the platen, and at the other end to the adjacent ends of the respective links 74 and to the extremities of a bar 75 in parallel relationship with the bar 60. One flange of an angle member 76 is secured to the side of the bar 60, the adjacent ends of the links 74 being pivotally connected to the other flange of said angle member. It will be apparent that this arrangement permits the bar 60 to be moved away from or toward the bar 59 thereby readily accommodating matrices of different widths. The bars 59 and 60 are at all times in parallel relationship and secured at right angles to the bar 58. The casting formed in the machine is absolutely true and smooth on each side and on its rear or bottom end, it being unnecessary to shave or trim off its sides and said end before using it. A matrix 77 of any desired width may be easily inserted in place on the platen by shifting the bar 60 away from the bar 59 and then raising obliquely the bars 59 and 58 and slipping the matrix under the bars 59 and 58. The bar 60 may then be swung upwardly away from the platen and pulled over toward the bar 59 the required distance and positioned over the adjacent edge of the matrix.

In preparing to dry or bake the wet papier-mâché flongs the bar 58 is removed, only the bars 59 and 60 being used to confine the heat between the platens. When the bar 58 is removed, the space between the bars 59 and 60 and the two platens forms a flue which is directly over the burner 50.

When it is desired to make a casting type high with a cored back, I secure a core member 78, see Figs. 11 and 12, to the face of the rear platen by a plurality of screws 79, the core member having a plurality of vertically extending ribs 80 and grooves 81. A transversely extending bar 82 is secured to the rear platen by screws 83 under the core member 78, the front side of said bar being flush with the front side of the ribs 80. When making castings of this type, the bar 58 is removed and a thinner bar 58^a is substituted therefor. The side bar 60 and the angle member 76 are also removed and an angle member or bar 84, substantially of the cross section shown in Fig. 11, is substituted therefor, one flange thereof being adapted to extend into any one of the grooves 81 of the core member and the other flange thereof being pivotally connected to the adjacent ends of the links 74 of the toggle mechanism for maintaining the member 84 in parallel relationship with the bar 59. In Fig. 11 the bar 84 is shown in position

to make a casting two columns wide. It will be obvious, however, that the bar 84 may be positioned in any of the grooves 81 so that castings of different widths may be made. It will be apparent when the platens are moved out of operative engagement that the casting will be carried upwardly with the front platen by reason of the bar 58^a engaging the bottom side of the casting, whereby the casting is readily extricated from the core member and without any chafing of the back sides of the ribs of the casting against the bottom of the grooves of the core member.

It will also be apparent from the foregoing description that a relatively thin casting, for example, a "skiver" may be made by moving the rear platen the desired distance toward the front platen, and by substituting in place of the bars 58, 59 and 60, relative thin bars for confining the metal, the principles of operation being precisely the same.

I do not intend to limit my invention to the details of construction shown and described herein, except only in so far as certain of the appended claims are specifically so limited, as it will be obvious that various modifications may be made by those skilled in the art without departing from the principles of the invention.

I claim:

1. In a machine of the class described, the combination of a supporting frame, a pair of platens, means connecting one of said platens to said frame and so arranged that the platen may occupy a substantially vertical position, and links connecting the other platen to said frame, said links being so arranged that the platen connected thereto may be moved either into co-operative relationship with the other platen or into a substantially horizontal position.

2. In a machine of the class described, the combination of a supporting frame, a pair of platens, links connecting one of said platens to said frame and so arranged that the platen may occupy a substantially vertical position, and links connecting the other platen to said frame and so arranged that the platen connected thereto may be moved either into co-operative relationship with the other platen or into a substantially horizontal position.

3. In a machine of the class described, the combination of a supporting frame, a pair of platens, means connecting one of said platens to said frame and so arranged that the platen may occupy a substantially vertical position, links connecting the other platen to said frame and so arranged that the platen connected thereto may be moved either inwardly into co-operative relationship with the other platen or outwardly into a substantially horizontal position, and

means to limit outward movement of said last-named platen.

4. In a machine of the class described, the combination of a frame member, a rear platen, means connecting said platen to said frame member and so arranged that the platen may occupy a substantially vertical position, a front platen member, means connecting said platen member to said frame member and so arranged that said platen member may be moved either inwardly into co-operative relationship with the rear platen or outwardly into a substantially horizontal position, a member pivoted on one of said first-named members, a link pivoted to the other of said first-named members and slidably connected to said pivoted member, and a compression spring encircling said link, for the purpose specified.

20 5. In a machine of the class described, the combination of a supporting frame, a pair of platens, means connecting one of said platens to said frame and so arranged that the platen may occupy a substantially vertical position, links connecting the other platen to said frame and so arranged that the platen connected thereto may be moved either inwardly into co-operative relationship with the other platen or outwardly into a substantially horizontal position, and spring means for assisting in the movement of said last-named platen from its vertical position to its horizontal position.

25 6. In a machine of the class described, the combination of a supporting frame, a pair of platens, means including a pair of links for connecting one of the platens to said frame, and means including a pair of links for connecting the other platen to said frame, said pairs of links being so arranged that they form a toggle when the platens are in co-operative relationship.

40 7. In a machine of the class described, the combination of a supporting frame, a pair of platens, means including a pair of links for connecting one of the platens to said frame and so arranged that the platen may occupy a substantially vertical position, and links connecting the other platen to said frame and so arranged that the platen connected thereto may be moved either into co-operative relationship with the other platen or into a substantially horizontal position, said first-named links and certain of the last-named links being so arranged that they form a toggle when the platens are in co-operative relationship.

45 8. In a machine of the class described, the combination of a supporting frame, a pair of platens, two pairs of links connecting one of the platens to said frame and so arranged that the platen may occupy a substantially vertical position, and two pairs of links connecting the other platen to said frame and so arranged that the platen con-

nected thereto may be moved either into co-operative relationship with the other platen or into a substantially horizontal position, one pair of said first-named links and one pair of said second-named links being so arranged that they form a toggle when the platens are in co-operative relationship.

50 9. In a machine of the class described, the combination of a supporting frame, a pair of platens, a pair of links connecting one of the platens at one end to said frame, a pair of links connecting the other platen at one end to said frame, said pairs of links being so arranged that they form a toggle when the platens are in co-operative relationship, and means to hold the other ends of said platens in said relationship.

55 10. In a machine of the class described, the combination of a supporting frame, a pair of platens, means including a pair of links for connecting one of the platens to said frame and so arranged that the platen may occupy a substantially vertical position, a pair of links connecting the other platen at one end to said frame, and means to hold said last-named platen at its other end in co-operative relationship with the other platen, said pairs of links being so arranged that they form a toggle when the platens are in said relationship.

60 11. In a machine of the class described, the combination of a supporting frame, a pair of platens, two pairs of links for connecting one of the platens to said frame and so arranged that the platen connected thereto may be moved into either a substantially vertical position or a substantially horizontal position, a pair of links for connecting the other platen at one end to said frame, and means to hold said last-named platen at its other end in co-operative relationship with the other platen, said last named links and one pair of the first-named links being so arranged that they form a toggle when the platens are in said relationship.

65 12. In a machine of the class described, the combination of a supporting frame, a pair of platens, means connecting one of said platens to said frame and arranged so that the platen may move into either its casting position or a position preliminary thereto, means connecting the other platen to the frame and arranged so that that platen may move into either a make-up position or its casting position but through an intermediate preliminary position, and means insuring said platens moving simultaneously either from their preliminary positions to their casting positions or from their casting positions to their preliminary positions, for the purpose specified.

70 13. In a machine of the class described, the combination of a supporting frame, a pair of platens, means connecting one of said platens to said frame and arranged so

that the platen may move into either its casting position or a position preliminary thereto, means for normally holding said last-named platen in its said preliminary position, means connecting the other platen to the frame and arranged so that that platen may move into either a make-up position or its casting position but through an intermediate preliminary position, and 5 members on said platens which co-engage while said platens are moving either from their preliminary positions to their casting positions or from their casting positions to their preliminary positions, for the purpose 10 specified. 15

14. In a machine of the class described, the combination of a supporting frame, a pair of platens, links connecting one of said platens to said frame and so arranged that 20 the platen may occupy a substantially vertical position and may move into either its casting position or a position preliminary thereto, links connecting the other platen to said frame and so arranged that that 25 platen may move into either a substantially horizontal make-up position or a substantially vertical casting position but through an intermediate preliminary position, and means insuring said platens moving simultaneously either from their preliminary positions to their casting positions or from their casting positions to their preliminary positions, for the purpose specified. 30

15. In a machine of the class described, the combination of a supporting frame, a pair of platens, links connecting one of said platens to said frame and so arranged that the platen may occupy a substantially vertical position and may move into either its 35 casting position or a position preliminary thereto, means for normally holding said last-named platen in its said preliminary position, links connecting the other platen to said frame and so arranged that that platen 40 may move into either a substantially horizontal make-up position or a substantially vertical casting position but through an intermediate preliminary position, and members on said platens which co-engage while 45 said platens are moving either from their preliminary positions to their casting positions or from their casting positions to their preliminary positions, for the purpose specified. 50

55 16. In a machine of the class described, the combination of a supporting frame, a pair of platens, means connecting one of the platens to said frame, bearings adjustably mounted on said frame, and links connecting the other platen to said respective bearings, for the purpose specified. 60

17. In a machine of the class described, the combination of a supporting frame, a pair of platens, means connecting one of the 65 platens to said frame, bearings adjustably

mounted on said frame, links connecting the other platen to said respective bearings, and adjusting screws journaled in said frame and operatively engaging said respective bearings, for the purpose specified. 70

18. In a machine of the class described, the combination of a pair of platens and means for clamping said platens together comprising a threaded stud pivoted at one end to one of said platens, a lug on the other platen adapted to be engaged by said stud, and a nut in the form of a handle on said stud. 75

19. In a machine of the class described, the combination of a frame, a pair of platens mounted on said frame, one of said platens carrying the matrix, a melting pot mounted on said frame, means to heat said pot, and independent means to heat the platen not carrying the matrix. 80 85

20. In a machine of the class described, the combination of a frame, a pair of platens mounted on said frame, one of said platens carrying the matrix, a melting pot mounted on said frame, a burner for heating said pot, a burner underneath but adjacent the platen not carrying the matrix for heating said platen, and means to supply fuel to said burners. 90

21. In a machine of the class described, the combination of a frame, a pair of platens mounted on said frame, one of said platens carrying the matrix, a melting pot mounted on said frame, a burner for heating said pot, two burners underneath but adjacent the platen not carrying the matrix for heating the front and rear sides of said platen, and means to supply fuel to said burners. 95 100

22. In a machine of the class described, the combination of a frame, a pair of spaced platens substantially vertically positioned on said frame when in casting position, one of said platens having a plurality of transverse ribs on one side, said ribs having apertures, covering material over said ribs whereby a flue is formed between said material and the adjacent side of the platen, and a burner positioned so that the currents of heated air may pass through said flue, for the purpose specified. 110 115

23. In a machine of the class described, the combination of a frame, a pair of spaced platens substantially vertically positioned on said frame when in casting position, one of said platens having a plurality of transverse ribs on one side, said ribs having apertures, covering material over said ribs whereby a flue is formed between said material and the adjacent side of the platen, a burner positioned so that currents of heated air may pass through said flue, and a burner positioned so that currents of heated air may pass upwardly in the space between said platens, for the purpose specified. 120 125

24. In a machine of the class described in- 130

cluding a pair of spaced platens, of means to confine the molten metal in the space therebetween comprising a bottom member, a pair of side members, means to attach said bottom member and one of said side members to one of said platens, and toggle mechanism carried by said last-named platen for adjustably connecting the other of said side members thereto.

10 25. In a machine of the class described including a pair of spaced platens, of means to confine the molten metal in the space therebetween comprising a bottom member, a pair of side members, means to attach said bottom member and one of said side members to one of said platens, and toggle mechanism swingingly carried by said last-named platen for adjustably connecting the other of said side members thereto.

20 26. In a machine of the class described including a pair of spaced platens, of means to confine the molten metal in the space therebetween comprising a bottom member, a pair of side members, means to attach said bottom member and one of said side members to one of said platens, a pair of jointed links, means pivotally connecting one end of each of said links to the other of said side members, means pivotally connecting the other end of each of said links to said last-named platen, and means connecting said jointed links, for the purpose described.

25 27. In a machine of the class described including a pair of spaced platens, of means to confine the molten metal in the space therebetween comprising a bottom member, a pair of side members, means to attach said bottom member and one of said side members to one

of said platens, pivoted means carried by said last-named platen, a pair of jointed links pivotally connected at one end to the other of said side members and at the other end to said pivoted means, and means connecting said jointed links, for the purpose specified.

45 28. In a machine of the class described including a pair of spaced platens, of means to confine the molten metal in the space therebetween comprising a side bar attached to one of said platens, a bottom member, a side member, an angle member having one leg fastened to one of said first-named members and the other leg interlockingly connected to the other of said first-named members, and means for holding said first-named members on said last-named platen.

50 29. In a machine of the class described including a pair of spaced platens, of means to confine the molten metal in the space therebetween comprising a side bar attached to one of said platens, a bottom member, a side member, means interlockingly connecting said bottom member to said last-named platen, and means interlockingly connecting said side member to said bottom member.

55 30. In a machine of the class described including a pair of spaced platens, of means to confine the molten metal in the space therebetween comprising a side bar, toggle means for connecting said bar to one of said platens, a bottom member, a side member, means interlockingly connecting said bottom member to said last-named platen, and means interlockingly connecting said side member to said bottom member.

65 HARVEY L. FISHER.
